TRANSFER SHEET AND METHOD OF
MAKING SAME

Havy Q. R. Crowder, Chicago, Ill.

Application June 1, 1931, Serial No. 541,469

8 Claims. (Cl. 41—33)

The present invention relates to a transfer sheet adapted particularly for the use of commercial artists in securing proper backgrounds and shadings and indicating different textures of material, etc.

My invention has for one of its objects the provision of a novel method by which my improved transfer sheet can be made. One form of the transfer sheet which may be made by this invention is disclosed in my Patent No. 1,820,867, granted August 25, 1931, on Transfer sheet and method of making same. The process is also disclosed in a general way in that patent. This application, however, is concerned with the process 10 of making the transfer sheet and also has to do with an improved form of transfer sheet not disclosed in my aforementioned patent.

Another object of this invention resides in the new form of transfer sheet which has certain advantages over the transfer sheet disclosed in my prior application, but which embodies some of the principles involved in that transfer sheet. In other words, the transfer sheet disclosed in this application is a specific improvement over that disclosed in my co-pending application.

A very important object of this invention is to distribute the wax which forms a portion of the transfer sheet, uniformly over the entire surface 30 of the sheet and over only one surface of the sheet. If the wax is permitted to form a layer on the opposite side of the sheet than that intended, the result is that I am unable to practice my method and for reasons which will appear presently.

Other objects of this invention will appear hereafter as the description thereof proceeds, the novel features, combinations and arrangements being clearly set forth in the appended claims.

In the drawings—

Fig. 1 is a perspective view of an apparatus used for carrying out my invention showing a transfer sheet in the process of formation;

Fig. 2 is a cross section through my transfer sheet showing the arrangement of the different layers thereof during one stage of its formation, the cross section being greatly magnified;

Fig. 3 illustrates an enlarged cross sectional view through my transfer sheet as sold on the market;

Fig. 4 illustrates a preliminary step in the formation of my transfer sheet;

Fig. 5 is an isometric view of the wiper bar used in carrying out my process;

Figs. 6 and 7 are cross sectional, frag-

mentary views of a device constructed according to my invention used with and without a float respectively;

Fig. 8 is a fragmentary perspective view looking in a direction perpendicular to the plane 8—8 in Fig. 1;

Fig. 9 is a view similar to Fig. 8 showing a straight-edged wiper bar in place of the wiper bar shown in Fig. 8;

Fig. 10 illustrates a modified form of wiper bar 85 which I find practical for most purposes; and

Figs. 11 and 12 illustrate the manner in which my improved sheet is used in practice.

The transfer sheet which I wish to form is one which can be used to transfer any suitable 70 type of marking bodily to a sheet of drawings or the like and which sheet comprises only three elements. These three elements are wax, ink and a transparent layer of flexible material of greater tensile strength than wax, or the equivalents of 75 these elements. The sheet comprises a thin layer of wax which carries any suitable ink markings and the inked markings are covered over by a layer of shellac, lacquer or the like. My principal feature is to provide a thin transparent 80 sheet or film as a body to hold the adhesive material such as wax and the ink in proper relation with each other to permit the same to be handled readily, the material forming the sheet or film, however, not preventing the scraping or cutting 85 away of undesired portions thereof after it has been applied, and which is transparent so as not to obstruct portions of the drawing. I will hereafter refer to the material being used as lacquer although it is to be understood that the term 90

is intended to include all equivalent materials such as shellac and other film forming compounds and transparent binders for holding the wax and ink. Thus the markings of ink or the like are protected both by the wax layer and the 95 layer of flexible transparent material such as lacquer, so that the markings cannot be smeared.

In accordance with a preferred method of practicing my invention, I first take a piece of very thin tissue paper which should be fairly porous 100 and also quite transparent, as well as being relatively tough. The tissue paper in the drawings is represented by the reference numeral 1. This is first moistened and laid on the flat japanned surface of the plate 2, or on any relatively smooth 105 surface. A rubber squeegee 3 having the metal portion 4 is used for the purpose of pressing the sheet of paper firmly against the smooth surface of the plate 2 and for removing the excess water from beneath the paper and from the surface 110

thereof. When the paper has been spread smoothly over the surface of the plate, the same is permitted to dry, but before being completely dry the surface thereof is coated with a layer of 5 glue 4' and the plate and coated sheet of paper are then set aside until the paper and glue have dried.

The glue which I have found most desirable for the purpose of this invention consists of a 10 mixture of glycerin, gum arabic and soft soap. These substances are mixed in approximately the following proportions:

	Per cent by weight
15 Glycerin	30
Gum arabic	35
Soft soap	35

This glue has a very uniform consistency and is 20 free from small lumps, which, of course, are very undesirable in a glue to be used in carrying out my invention. At the same time, such a glue will flow uniformly over the surface upon which it is applied and will not leave small openings on the 25 surface, as often occur with other forms of glue. For instance, little glue bubbles will not form and later break to expose a portion of the sheet of paper therebeneath.

After the glue has been prepared, I add there- 30 to enough distilled water to reduce the glue to the desired consistency for spreading on the surface of the sheet of paper. The glue is thereafter spread on the surface of the paper in a very thin coat or film either by a brush or by means of a 35 spray or any other desired means.

It takes approximately one hour for the glue to dry after being applied to the paper, and when I refer to the glue drying, I do not in any sense 40 intend to convey the idea that the glue forms a hard surface on the paper, because it does not. The glue, on the other hand, is relatively pliable and after the glue is dried the sheet of paper can be folded without cracking the glue, for the 45 glue forms a very very thin layer and the tissue paper is very thin. Therefore the bending of the paper does not have a tendency to distort either the paper or the glue. After the glue is dry I spray or brush lacquer over the surface of the 50 glue to form a thin layer 32 upon which the inked markings are impressed.

When the lacquer is dry, the sheet of paper is stripped from the plate 2 and put through the printing press which prints on the surface of the lacquer the desired configurations which are to be transferred to a selected surface. In the present instance the configuration assumes the form of straight parallel lines 5, shown in dotted lines in Fig. 1, in view of the fact that in that figure the lines are on the exposed side of the paper. 55 It will be understood, however, that any suitable 60 type of printing may be placed on the surface of the lacquer.

The next and perhaps most important step of 65 my process resides in the forming of a thin layer of wax over the surface of the printing which appears on the lacquer, as well as covering any exposed portions of the lacquer. This process in general consists of making a bath of the wax and flowing the sheet of material on the top of the 70 wax with the printed side thereof facing the surface of the wax. Means is provided for heating the bath of wax and it is kept at a very fluid consistency so that only a thin layer of the wax remains on the sheet of paper when the same 75 is withdrawn therefrom. This sheet of wax dries

substantially as quickly as the same is withdrawn from the bath and this enables one to stack the finished sheets, one upon the other.

The apparatus for applying the wax is best 80 illustrated in Figs. 1, 6 and 8. An electric heater 6, having the electric cord 7 leading therefrom to a suitable source of electrical energy, is used for the purpose of heating the wax bath. A pan 8, of rectangular form and relatively shallow, is placed on the heater and the wax is placed in the pan and heated to the desired fluid consistency.

The wax is made from approximately 50% of 85 bleached beeswax and 50% paraffin, both percentages being by weight, and being represented in Figs. 2 and 3 by the reference numeral 9. My invention is not limited to using this form of wax, but this particular compound has been found quite desirable, as it is relatively uniform in consistency and flows readily over the surface of the sheet.

Near one end of the pan 8 there is arranged a 90 wiper bar 10 rotatably supported by the brackets 11 on the opposite sides of the pan. This wiper bar is substantially square in cross section and has each of the longitudinal edges thereof provided with a series of notches designated by the 95 reference numerals 12, 13, 14 and 15. These notches are substantially V-shaped and are of different depths and widths. The purpose of these notches will appear hereinafter. A spring 16 secured by means of the rivets 17 to the inside vertical side of the pan 8, is adapted to engage the adjacent flat side of the wiper bar 10 and prevent its rotation under ordinary circumstances. However, the bar may be grasped and rotated by 100 hand to present any one of the desired edges at the operative position for accomplishing the result hereinafter to be more clearly pointed out.

I also place a rectangular float 18 on the 105 surface of the wax. This float can readily be constructed of thin pieces of wood or can be constructed in any other manner desired. Even metal with hollow chambers may be used for this purpose. I also provide a rest bar 19 which is merely laid across the pan and supported by the 110 upper opposite edges thereof, as quite clearly 115 illustrated in Fig. 1.

I next select the notched edge of the bar 10 which I desire to use in this process and I will assume that in Fig. 1 I will use the edge 12 for this 120 purpose. This edge should therefore be positioned at the position illustrated therefor in Fig. 1, as this is the only operative edge of the bar. The sheet of paper with the glue, lacquer and the 125 inked markings thereon is held with the ink facing downward. I support one end 20 of the paper 1 by the bar 19 while I hold the other end 21 of the paper in my hands. The paper is therefore supported at opposite ends thereof, but not in the middle and this middle portion is permitted to 130 drop down into engagement with the surface of the wax, beginning with that end of the paper being held in my hands. I next draw the paper over the surface of the wax and then over the 135 surface of the bar, the wax clinging to the surface of the paper and being carried into engagement with the scraping edge 12 of the bar, which scraping edge removes a certain percentage of the wax and leaves only the desired thickness of the wax 140 on the surface of the sheet.

The reason for providing the rest bar 19 is so 145 that the sheet of paper will not be in contact with the surface of the wax for too great a period of time. The bar may be shifted longitudinally of the pan, if desired, and no means is necessary to 150

- hold this bar in place, although such a means could be used, if desired. The reason for providing the float is quite obvious from an inspection of Figs. 6 and 7 in which I have shown the bath with and without the float. If the float is provided, as in Fig. 6, the edge of the paper is held out of contact with the wax, or if there is wax on the surface of the float, the same is not of sufficient depth to run over the edge 10 of the sheet and onto the upper surface thereof. It is very important that the upper surface of the sheet does not have wax thereon, at least over that portion of the sheet which contains the markings. Therefore, if the float were not used, the edge of the sheet might sink below the surface of the wax, as seen in Fig. 7, and portions of the wax, such as 22, may run over the upper surface of the sheet and form a coating of wax, which will prevent the penetration of water 20 through the sheet for a purpose to be pointed out hereinafter in connection with the use of the sheet. Therefore, by using the float, I am enabled to keep the upper surface of the sheet free from wax and thereby produce a better transfer sheet.
- The notched bar 10 performs a very important part in the process, for this notched bar insures a uniform distribution of the wax over the surface of the sheet and can be used as a gauge for 30 gauging the thickness of the wax and also prevents any portions of the sheet from having less than the required amount of wax thereon. In Fig. 8 I have shown a notched bar and in Fig. 9 I have shown a bar without notches and having 35 a straight scraping edge thereon. If the sheet of paper is drawn over the edge of the bar 23 having the straight edge 24 thereon, a great proportion of the wax is scraped off the surface of the sheet and ordinarily with a skilled operator and 40 with other conditions just right, it is possible to form a uniform layer on the sheet as the paper is drawn over the edge 24, but occasionally the sheet being prepared is pressed against the edge 24 with a greater pressure at certain points than at others. The result is that at certain points such as at 25, only a thin layer of wax is provided or in a great many instances, substantially no wax will adhere to the surface of the sheet. This exposes a portion of the inked markings, or in many 45 instances, does not provide a sufficient quantity of wax over the inked markings to enable one to use the sheet for the purpose intended. This will appear hereinafter in the description of the manner of using the sheet.
- With the notched bar 10, however, the notches will permit a certain quantity of the wax to pass the scraping edge and only the portions of the sheet which contact directly with the points can have the wax scraped therefrom. Therefore, as the sheet is drawn over the edge 55 of the bar, there are a series of raised portions of melted wax which quickly spread and unite with each other to form a uniform film or sheet of wax over the surfaces of the inked markings and lacquer. By using notches of different depths I am enabled to vary the thickness of the sheet of wax which is formed over the inked markings.
- Instead of using a bar such as illustrated in 60 Figs. 1, 5 and 8, I may use instead a square bar about which there is wound a wire 27, the adjacent turns of the wire being in abutting relationship to each other. This is a very easy way to form notches of uniform depths throughout 70 the entire length of the bar although it does not provide a bar having notches of different depths. Ordinarily, in carrying out my process, however, it is not necessary to have grooves of different depths.
- In using the type of sheet described in my aforementioned application, it is necessary to moisten the back of the sheet when using the same. This has been found to be objectionable in some instances and therefore I have devised a means for preparing a sheet of material which does not have to be wetted in order to use the same. 80
- I take the sheet of paper produced in the manner which has just been described, lay the same with the waxed surface down and thereafter apply water to the upper surface of the sheet to soften the layer of glue. I then strip the paper from the sheet of lacquer so that all that remains is a sheet comprising layers of wax and lacquer with the markings carried therebetween. While it is not absolutely necessary to wash the remaining portions of the glue from the surface of the lacquer, I prefer to do this before placing the same on the market. If desired, and the paper is sufficiently transparent, it may be left on the transfer sheet, in which 90 case it takes the place of the layer of lacquer with or without the layer of glue. The sheet is then ready for the artist who is to use the same. Therefore when the sheet is burnished down as hereinafter described, the burnishing does not 100 cause the ink to smear.
- This sheet is applied in substantially the same manner as described for the sheet disclosed in my aforementioned application. However, it is unnecessary for the artist to use water to soften 110 the glue, as in the use of the former sheet. The sheet of wax, or portions thereof, may be laid on the surface 30 and an additional sheet 31 of plain paper, transparent or otherwise, may be (but need not be) laid over the sheet of wax 115 with the wax surface thereof against the surface 30 and the back of the paper 31 pressed against the sheet, with a bone stylus 28 or the like over and throughout a predetermined area of the surface 30 indicated by the large letter 120 "E" in Figs. 11 and 12. This causes the wax to adhere to the surface 30 and the paper 31 can be removed without wetting the same. The artist then merely tears or cuts away the portions of the sheet which do not adhere to the 125 surface 30 and then trims or scrapes away portions of the wax (with its superimposed layer or layers) for shading or scrapes away those portions which adhere to the paper and which extend beyond the area desired to be covered, 130 as in my aforementioned patent.
- In using my process to form a transfer sheet which has a tissue paper backing such as described in my aforementioned patent, I do not use the lacquer, but instead I print directly on 135 the surface of the glue and then coat the sheet with wax as described in connection with the preparation of the sheet shown in Fig. 3. When using the tissue paper backing, it is not necessary that a heavy coating of wax be applied to 140 the sheet as where the tissue paper backing is not used. It will be understood that my process is substantially the same for the formation of either sheet described but in forming the sheet shown in Fig. 3, it is desirable to add a layer 145 of lacquer which acts as a binder to hold the sheet together after it is formed. I wish to have it understood that the lacquer, while acting as a binder and as a protecting coating for the ink, is not sufficiently thick to prevent the tear- 150

ing away, or scraping, of portions of the wax from the remainder of the sheet.

In Fig. 3 I have shown the sheet made according to my invention in which the tissue paper 5 has been removed and also the glue. The surface of the sheet is covered by a layer of lacquer 32 so that the resulting sheet comprises a layer of wax 9, a layer of lacquer 32, and inked markings 5 arranged between the two layers, the markings being visible through the layer of lacquer, and the markings and the layer of lacquer being adhered to the drawing or other surface to which the background is applied, through the intermediation of the wax which provides an adhesive 10 operative solely by relatively light pressure and which can be readily removed without marring the surface. (See Fig. 12).

Due to the fact that the ink is entirely closed within a protecting cover of wax and lacquer, 20 it is possible for me to use dry or moist ink in carrying out my process but even a dry ink has some tendency to smear if exposed. The ink is transferred bodily and does not rely upon the characteristics of the ink for its usefulness in being 25 transferred to the desired surface. In former methods, ink has been mixed with wax and applied to a sheet in a printing process, but the wax in those processes was merely mixed with the ink to keep the same moist and to prevent the same from drying out or to render the ink moist 30 under the application of heat so that when the sheet is used the ink itself may be impressed upon the surface to which the same is to be transferred. In other words, with former devices it 35 has been necessary to maintain the ink in a moist state so that it could be transferred. With applicant's device, however, the transfer is accomplished by means of the wax, and the ink, therefore, may be dry ink instead of the ordinary non-drying ink.

Obviously other changes may be made in the particular construction and arrangement of parts without departing from the spirit of this invention or from the scope of the appended 45 claims.

Having thus described my invention, what I claim as new and desire to obtain by Letters Patent is:

1. The method of preparing a transfer sheet 50 comprising the steps of moistening a sheet of relatively thin paper, pressing it down firmly on a smooth surface, applying a coating of glue thereto while said sheet is wet, applying lacquer to the surface of said glue, applying markings to the 55 surface of said lacquer after it is dry, and covering said lacquer and markings with a compound of wax and paraffin.

2. The method of preparing a transfer sheet 60 comprising the steps of moistening a sheet of relatively thin paper, pressing it down firmly on a smooth surface, applying a coating of glue thereto, applying lacquer to said glue, applying markings to the surface of said lacquer after it is dry, and covering said glue and markings with a compound of wax and paraffin.

3. A transfer sheet comprising a layer of lacquer, an exposed layer of wax, and markings carried between said layers, said markings being

protected by both layers and visible through the layer of lacquer.

4. The method of preparing a transfer sheet 80 comprising the steps of moistening a sheet of relatively thin paper, pressing the same firmly down on a smooth surface, applying a coating of glue thereto while said sheet is wet, applying a thin coating of liquid to the surface of said glue which liquid is of a character which dries in a thin film having appreciable tenacity, applying markings to the surface of said film, and covering the film and markings with a compound of wax and paraffin, said film having greater tensile strength than said paraffin.

5. The method of forming a transfer sheet 85 which comprises the steps of applying a coating of glue to a sheet of material on one side thereof, forming a thin film of lacquer on the surface of said glue, applying ink markings to the surface of said lacquer after the latter has dried, and covering the markings and exposed portions of the lacquer with a coating of wax.

6. A sheet of the class described comprising a thin transparent layer of wax having one exposed 90 surface, a continuous exposed layer of thin transparent friable material of greater tensile strength than said wax to reinforce said layer of wax, and markings carried by said combined layers therebetween, said markings being visible from both sides of the sheet and being protected by both 95 layers.

7. In a transfer adapted to provide an artist's 100 background, the combination with a drawing surface to be covered, of a layer of slightly adhesive material adhered to a predetermined area of said surface by the application of pressure but readily removable therefrom without marring the surface, a superimposed continuous layer of transparent 105 flexible material of greater tensile strength than the adhesive material substantially co-terminous with said area and adhered to said surface through the intermediation of the adhesive material, and markings of ink or the like between said layers in direct contact with each layer and protected by both layers, said transfer 110 being thereby rendered substantially integral with said surface and said markings being visible thereon through the layer of transparent material.

8. In a transfer adapted to provide an artist's 115 background, the combination with a drawing surface to be covered, of a layer of solidified wax adhered to a predetermined area of said surface by the application of pressure but readily removable therefrom without marring the surface, a 120 superimposed continuous layer of transparent flexible material of greater tensile strength than the solidified wax substantially co-terminous with said area and adhered to said surface through the intermediation of the solidified wax, 125 and markings of ink or the like between said layers in direct contact with the wax and protected by both layers, said transfer being thereby rendered substantially integral with said surface and said markings being visible thereon 130 through the layer of transparent material.

HARRY Q. R. CROWDER.
